FURNACE WALL

Herbert E. Preston, Philadelphia, Pa., assignor to
American Engineering Company, Philadelphia,
Pa., a corporation of Pennsylvania

Application August 6, 1931, Serial No. 555,548

3 Claims. (Cl. 122—6)

This invention relates to improvements in furnace wall structures, and while applicable in principle to various types of furnaces, has an application of particular value to the walls of stoker-fed furnaces. In stoker-fed furnaces, and particularly with stokers of the multiple under-feed type, such for example as shown in the U. S. patent of Maxwell Alpern, No. 1,443,202, it is customary to provide, particularly in those parts 5 more directly subjected to the higher temperatures, fluid-cooled wall sections or panels, which are better adapted than the ordinary walls to withstand the high temperature conditions, and which have other advantages hereinafter set forth. For maximum efficiency it is desirable to maintain these fluid-cooled walls free from slag, which, normally forming on the upper portions 10 of the wall, flow down the surface of the latter to the fuel-bed. With stokers of the above- 15 mentioned type it is of particular importance to avoid slag accretions on the lower portions of the wall immediately adjacent the fuel-bed, since such accretions interfere with a normal feeding of the fuel in the retorts.

20 A principal object of my invention, therefore, is to provide novel and improved means for maintaining these or other portions of the walls of a furnace, and particularly of stoker-fed furnaces, free from slag accumulations.

25 Another object of the invention is to provide a fluid-cooled wall structure, comprising as a built-in part thereof, means for preventing accumulations of slag on the surfaces thereof.

30 A more specific object of the invention is to provide a wall structure having novel means for deflecting molten slag flowing down the wall from those portions thereof immediately adjacent the fuel-bed.

35 Still another object of the invention is to provide in a stoker furnace, means for diverting molten slag from the wall surfaces at a point above the fuel-bed directly into the retorts, whereby the said slag is carried off to the ash-pit by normal feeding of the fuel through the stoker.

40 A further object of the invention is to provide a fluid-cooled panel structure for the walls of furnaces, comprising simple and highly effective means for deflecting molten slag from the upper portion of the panel, whereby the underlying 45 surface portions of the panel remain clear of slag formations.

45 A still further and more specific object of the invention is to provide a fluid-cooled wall structure for furnaces, comprising fluid circulating 50 ducts and facing elements or blocks overlying said

tubes, wherein certain of said blocks constitute means for deflecting molten slag from the surface of the panel.

The invention further resides in certain novel structural details hereinafter set forth and illustrated in the attached drawings, in which:

5 Fig. 1 is a more or less diagrammatic longitudinal sectional view through the combustion chamber of a stoker furnace, wherein the walls are made in accordance with my invention;

10 Fig. 2 is a section on the line 2—2, Fig. 1;

Fig. 3 is a view in perspective of one of the elements of the wall structure shown in Fig. 2; and

15 Fig. 4 is a fragmentary enlargement of a portion of the rear wall of the furnace shown in Fig. 1.

With reference to Fig. 1 of the drawings, 1 is the front wall, 2 the rear wall, and 3 one of the side walls of a stoker furnace. The stoker indicated at 4 is of the under-feed multiple retort type, including an inclined series of alternately arranged retorts and tuyères, one of the retorts lying immediately adjacent each of the side walls 3. This stoker extends downwardly from the front wall 1 and terminates in an ash-pit 5, the fuel being introduced to the retorts through suitable openings in the front wall 1 and being fed during combustion downwardly through the retorts, the ash residue being deposited in the ash-pit.

20 The side walls 3 are provided in the present instance with a fluid-cooled panel 6, extending from the front wall 1 to the rear wall 2, said panels lying immediately adjacent the sides of the stoker and being inclined at an angle corresponding approximately to the inclination of the latter. These panels accordingly form side abutments for the upper portions of the fuel-bed. As illustrated in Fig. 1, the panel comprises a series

25 of tubes 7, which extend longitudinally of the panel from a header 8 at the front wall to a header 9 behind the rear wall 2. The headers 8 and 9 are connected through pipes 11 and 12 in a circulating fluid system. The panel further

30 comprises a series of facing blocks 13, which are suitably secured against the inner faces of the tubes and form the effective inner wall surface. These blocks may be made of any suitable refractory material such as metal, refractory clay or brick, or a combination of both. The rear wall 2 of the furnace comprises a series of upright tubes 14, corresponding to the tubes 7 of the side panel and a plurality of facing elements 15 are secured against the sides of the tubes to form the inner effective wall surface.

35 The construction of the side wall 3 is more

clearly shown in Fig. 2. As therein illustrated, the said wall is provided with an elongated opening 16, which is defined by a suitable supporting frame, the panel 6 being secured at the inner 5 end of this opening with its inner face substantially flush with the adjacent portions of the inner wall surface. The facing blocks 13 are adapted for location between adjacent tubes, being formed with curved recesses which contact a 10 substantial portion of the outer surfaces of the tubes between which they are inserted. These blocks are drawn securely against the tubes and are held in position by studs 17, which extend rearwardly therefrom between the tubes and 15 through a clamp 18, which in the present instance is in the form of a bar engaging the backs of the tubes of the entire series. The lower series of blocks 13a are formed to embrace the lower tube of the series and to contact 20 the adjacent tube, the upper series of blocks 13b being similarly formed to embrace the upper tube of the series and to contact the next lower tube. Fluid-cooled panels of this general construction are illustrated in the application of 25 Edward Wheeler, No. 250,237, filed January 28, 1928.

In accordance with my invention, I form the upper series of blocks 13b as illustrated in Fig. 3. This block is of greater thickness at its lower 30 edge than at the upper edge, so that when secured in position against the tube the said lower end projects outwardly beyond the face of the wall as defined by the outer faces of the blocks 13 and 13a. The series of blocks 13b thus forms in effect an inclined ledge overhanging the entire panel. As a consequence, molten slag flowing down the upper portions of the wall on to the panel is deflected away from the surface of the latter and drips directly into the fuel-bed. 35 Preferably the overhang of the blocks 13b is such that the slag will fall directly into the stoker retorts adjacent the panels, whereby the slag will be carried downwardly with the fuel in the normal feeding operation and will eventually be discharged into the ash-pit. A characteristic of 40 fluid-cooled panels of this type is their tendency to prevent heavy formations of slag, and by deflecting the molten slag flowing from the upper portions of the wall as described above, the entire panel is maintained substantially free 45 from slag. The efficiency of the wall thereby remains at a maximum. Also, slag accumulations at the lower portions of the panel which abuts the fuel-bed are substantially eliminated, 50 so that there is no interference with the normal feeding of the fuel in the side retorts of the stoker.

The invention provides an extremely simple and highly practical solution of the slag problem, particularly in connection with stoker furnaces of 55 the type set forth, and involves no material departure in the normal construction of the wall.

Substantially the same principle is employed in the rear wall 2 for maintaining the wall substantially free from slag. As illustrated in Fig. 60 4, certain of the transverse series of blocks 14, identified by the reference numeral 14a, are formed to provide deflecting ledges from which the slag flowing down the wall onto the fluid-

cooled portion is deflected from the surface of the latter directly into the ash-pit 5. In the present instance I have shown two of the transverse series of blocks so formed and it will be apparent that still others of the facing blocks may 5 be so formed if required.

While I have illustrated my invention as applied to the side and rear walls of a stoker furnace, it will be apparent that the same principle may be employed to advantage in any furnace wall structure of this general type, either with or without the fluid-cooled feature. It will also be apparent that the structural form of the elements 13b and 14a may vary considerably without departure from the invention. Furthermore, while in the 15 illustrated embodiment the invention is applied to a wall structure in which fluid-carrying tubes are provided throughout with facing blocks, it will be apparent that the same principle of slag diversion may be applied to walls in which the tubes are 20 exposed for preventing molten slag flowing onto the latter.

I claim:

1. In a furnace, the combination with a fuel supporting structure, of a plurality of liquid conducting tubes provided at one side of said structure, and a plurality of rows of protective elements detachably secured against the tubes and providing a wall surface bounding the fuel bed, one of said rows of protective elements projecting 30 inwardly from said wall surface to form a ledge overhanging the fuel bed whereby any slag flowing down the wall is diverted away from the wall surface therebelow, and into the fuel bed, and the inner surfaces of said last mentioned elements inclining downwardly and inwardly.

2. In a furnace wall, a plurality of fluid conducting tubes provided in said wall, rows of protective blocks secured to said tubes in side to side relation forming a smooth continuous surface, one or more of said rows of blocks projecting inwardly from said wall to form an overhanging ledge whereby any slag flowing down the wall is diverted away from the portion of the wall therebelow, said last mentioned rows of blocks being spaced vertically and the inner surfaces thereof inclining downwardly and inwardly, tube receiving recesses in the outer side of all of said blocks, and means for clamping said blocks into intimate contact with said tubes.

3. In a furnace wall, having an opening inclined to the horizontal, a protective structure substantially closing one side of said opening, said protective structure comprising a series of inclined tubes, rows of protective blocks secured to said tubes, the inner surface of said blocks being substantially flush with the inner surface of said wall forming a smooth continuous surface, one or more of said rows of blocks projecting inwardly from said wall to form an overhanging ledge 60 whereby any slag flowing down the wall is diverted from the portion of the wall therebelow, the inner surfaces of said last mentioned blocks inclining downwardly and inwardly, one or more tube receiving recesses provided in the outer side of all 65 of said blocks, and means for clamping said blocks into intimate contact with said tubes.

HERBERT E. PRESTON.
